UNITED STATES PATENT OFFICE.

SAMUEL R. FRAIM, OF LANCASTER, PENNSYLVANIA, ASSIGNOR TO THE E. T. FRAIM
LOCK COMPANY, A CORPORATION OF PENNSYLVANIA.

PADLOCK.

1,243,151.

Specification of Letters Patent. Patented Oct. 16, 1917.

Application filed May 1, 1916. Serial No. 94,819.

To all whom it may concern:

Be it known that I, SAMUEL R. FRAIM, a citizen of the United States, residing at Lancaster, in the county of Lancaster and State of Pennsylvania, have invented certain new and useful Improvements in Padlocks, of which the following is a specification.

This invention relates to padlocks and it 10 relates particularly, to locks of this kind in which sliding shackles are employed.

The primary object of the invention is to provide simple, cheap and easily assembled means whereby the parts for securing and 15 releasing one arm of the shackle of a padlock shall be maintained in proper operative position within the lock without necessitating the attachment of such parts to the lock casing, thereby dispensing with extraneous 20 attaching means and the labor incident to securing them in place, and also preventing defacing the outside of the casing by exposed screws or rivets. A further object of the invention is to provide a lock of the 25 kind referred to wherein the means for retaining the locking spring and the spring for projecting the shackle from the lock when released, shall be of such construction as to permit of their being punched from 30 sheet metal and of being connected by riveting the parts to each other thereby cheapening the structure and reducing the labor necessary to secure the parts together. I have further in view the object of so 35 constructing and arranging the means for holding the locking spring and the spring for projecting the shackle from the lock when released, that they together with the springs shall be capable of being joined together.

40 and introduced into the casing in a complete form, and be retained in the casing in proper operative position without requiring attachment to the casing by screws, rivets, or the like, which latter means ordinarily not only adds to the cost of material and labor but results in detracting from the outward appearance of the lock. I have also in view the production of locking means, and means for projecting the shackle from the lock 50 which shall be of a form to be certain in operation, and the parts whereof shall be capable of long use without undue wear.

With these objects in view the invention consists of a padlock having the generic and 55 specific features of construction and ar-

angement of the parts substantially as hereinafter described and claimed.

The invention is illustrated in the accompanying drawing in which,

Figure 1 is a side elevation of a lock, 60 one face plate thereof and one of the retaining disks employed being removed, the shackle being shown in a locked position by full lines and in an unlocked position by dotted lines;

Fig. 2 is a side view of the shackle;

Fig. 3 is a perspective view showing one of the disks to which the means for retaining the locking spring and the spring for projecting the shackle from the lock are attached;

Fig. 4 is a perspective view showing the second disk for securing the operative springs in place;

Fig. 5 is a perspective view of the locking 75 spring; and,

Fig. 6 is a side view of the key employed.

Fig. 7 is a sectional view of the parts of my lock in assembled position.

In this drawing 1 represents the body of 80 the padlock which may be of any desired form and which has at one side thereof two openings 2, for the reception of the two arms 3 and 4 of the shackle 5. The casing has formed therein on the side opposite to that 85 in which the shackle openings are located, a key opening 6 in which is secured a rotatable slotted key disk 7.

The body of the padlock has formed in it a chamber which is preferably but not necessarily circular in form, for the reception of the parts by which the shackle is locked and by which it is projected when released from the locking means. Arranged within the chamber in the lock case are two disks 8 and 90 9 which are secured together and are separated apart a distance such that when they are placed in the chamber each will be adjacent to an outside face of the lock case.

Secured to the disks 8 and 9 are two plates 10 and 11 arranged parallel to each other and extending transversely of the lock. Each of these plates has projecting from its edges nibs 12 adapted to enter corresponding openings in the respective disks and be 105 secured to the latter by riveting the ends. Arranged between the plates 10 and 11 is a spring 13 which is bent back upon itself to form a substantially U-shaped body. The spring is of a width corresponding to the 110

space between the plates 10 and 11 and the ends thereof project a short distance beyond one end of the shorter plate 10, but is supported its entire length upon the longer plate 11. The plate 10 has therein an opening 14 for the reception of the reduced end of a key, and the plate 11 has in it, opposite the opening 14, a ward opening 15 for the reception of the key. The ends of the plate 11 which 10 projects beyond the plate 10 has in it an opening 16 through which the lower end of the arm 4 of the shackle projects and by which it is guided in its longitudinal movements.

15 Extending between the disks 8 and 9 at a point in line with the opening 16 in the plate 11 is a bar 17 having extending from one face thereof a stud 18 on which is arranged a coil spring 19 which bears against the end of 20 the arm 4 of the shackle and by which it is moved outward when released from the locking means. The stud 18 may be of any form and may either be integral with the bar, or as herein shown may be a separate piece riveted or otherwise connected to the bar.

25 The disk 9 has connected to it a projecting lip 20 which engages a portion of the arm 4 of the shackle and which when the parts of the lock are assembled prevents the separation of the shackle from the case of the lock. The lip has formed with it an arm 21 having a reduced end 22 which enters an opening in the disk 8 and to which it is secured by riveting.

30 35 The arm 4 of the shackle has a socket 23 formed in its end, such socket being of a size to receive the coil spring 19 which is normally maintained under tension and tends to move the shackle outward from the 40 case of the padlock. The arm is formed a short distance from the end on the opposite faces thereof with notches 24 of a length corresponding to the width of the locking spring 13. When the shackle is pushed into 45 the lock the ends of the spring 13 enter the notches and the ends of the latter form stops against which the edges of the ends of the spring bear and by which the shackle is held against the longitudinal movement.

50 55 Above the notches 24 the arm 4 is formed with a circumferential groove 25 into which the lip 20 projects, the parts being so arranged in relation to each other that free rotation of the shackle arm is permitted and its withdrawal from the case prevented. The side of the shackle above the groove 25 which is adjacent to the lip 20 is cut away as shown at the point 26 so that when both the arms of the shackle are in their openings 60 in the case such cut away portion is opposite the lip 20 and the latter therefore presents no obstruction to the inward movement of the shackle. When however the shackle is moved outward from the case a predetermined distance to allow the arm 3 of the

shackle to be swung away from its opening in the body, the lip contacts with the lower face of the groove 25 and checks the outward movement of the shackle preventing the withdrawal of the latter from the case. 70 Each of the disks 8 and 9 has extending from one edge thereof a small lip 26 which enters a socket in the inner face of the chamber of the lock. By this means the placing of the disks in order to properly locate the 75 parts carried by them, and means for preventing the turning of the disks in the case is provided.

75 In assembling the lock, the plates 10 and 11 are secured to the disk 8 and are attached 80 thereto by riveting the end of the nibs 12, and the bar 17 is also connected to the disk in a similar manner. The spring 13 is placed between the plates 10 and 11, the spring 19 is placed around the stud 18, and the disk 85 with the parts carried thereby is introduced and the ends of the spring are forced apart after which the shackle is introduced. The arm 4 of the shackle is passed through the opening 16 in the plate 11, and is moved into 90 the case until checked by the bar 17, at which time the end of the spring 19 is seated in the socket in the end of the arm. The disk is then introduced and is secured in place by riveting the nibs extending from the plates 95 10 and 11 and those extending from the bar 17 and from the end of the arm 21. Finally the face plates of the lock are arranged outside the disks and are secured in place in any suitable manner, preferably by spinning the 100 edges of the chamber of the lock over the face plates and in this way a smooth outer appearance free from exposed screws or rivets is presented.

105 I claim:

1. A padlock comprising a case, a disk arranged in the case, unattached thereto and having transverse plates secured to it, a spring bent back upon itself and arranged between the plates, a shackle having an arm 110 provided with oppositely arranged flattened faces extending between the ends of the spring, a second disk arranged in the case, attached to the first and spaced therefrom, and face plates secured to the body. 115

2. A padlock comprising a case, two disks arranged in the case, two plates extending between and transversely of the disks and having nibs riveted to the disks, a locking spring bent back upon itself and arranged 120 between the plates, a bar having a stud extended between the disks, a coil spring located on the stud, and a shackle having an arm provided with oppositely located flattened faces adapted to receive the locking 125 spring, and having a socket in its end adapted to receive the coil spring.

3. A padlock comprising a shackle having one arm thereof provided in its end with a socket, having oppositely located flattened 130

- portions adjacent to the end, a circumferential groove adjacent to the flattened portions, and a second flattened portion on the other side of the groove, a locking spring bent back upon and adapted to engage the oppositely arranged flattened portion, a coil spring located in the socket, and a lip adapted to project into the groove and located adjacent to the second flattened portion of the arm.
4. A padlock comprising a case, two disks located in the case, spaced apart, and unattached to the case, transverse plates extending between the disks and attached thereto, a locking spring bent back upon itself and arranged between the plates, a lip extending between the plates, a bar having a stud and located between the plates, a coil spring arranged on the stud, and a shackle having one arm thereof provided in its end 20 with a socket receiving the coil spring, having flattened portions adapted to receive the ends of the locking spring, and being provided with a second flattened portion and with a circumferential groove adapted to 25 receive the lip.
5. In testimony whereof I affix my signature in the presence of two witnesses.
